UNITED STATES PATENT OFFICE.

EDWARD R. IVES, OF BRIDGEPORT, CONNECTICUT.

DESIGN FOR AUTOMATIC TOYS.

Specification forming part of Design No. **7,431**, dated May 12, 1874; application filed April 20, 1874.
[Term of Patent 3½ years.]

To all whom it may concern:

Be it known that I, EDWARD R. IVES, of Bridgeport, county of Fairfield, State of Connecticut, have invented a certain new and useful Design for Mechanical Toys; and do hereby declare that the following is a full and exact description thereof.

The nature of my design is fully shown in the accompanying drawings.

A represents a common barrel, set upon its

end. Upon the top of this barrel is a standing figure, B, which is connected to the barrel.

What I claim is—

The design for an automatic toy, formed by the barrel A and the figure B thereupon, substantially as described and shown.

EDWARD R. IVES.
